Primary Examiner — Jennifer Rivard(74) *Attorney, Agent, or Firm* — Hamre, Schumann, Mueller & Larson, P.C.(57) **CLAIM**

The ornamental design for a container for cosmetics, as shown and described.

DESCRIPTION

FIG. 1 is a perspective of a container for cosmetics showing our new design;

FIG. 2 is a front elevational view thereof, a rear elevational view thereof is identical;

FIG. 3 is a left side view thereof, a right side view thereof is identical;

FIG. 4 is a top plan view thereof; and,

FIG. 5 is a bottom plan view thereof.

Contour lines indicate the contour and character of surfaces. Oblique contour lines indicate translucent materials.
